ERNST BARTEN, OF BUSCHHUTEN, NEAR SIEGEN, GERMANY

ROLLING MILL AND METHOD

Application filed June 29, 1929, Serial No. 374,642, and in Germany May 2, 1925.

My invention relates to rolling mills and to methods of rolling, and has been designed particularly for the rolling of metal blanks of the character of sheets, bands or strips. 5 The object of my invention is to obtain a very efficient operation, and to provide an apparatus possessing great advantages as to compactness, flexibility in operation, and ease of handling the blanks under treatment. 10 Important advantages are secured, in my invention, by providing special connecting members adapted to be fastened to the ends of the blank, and to move close up to the rolls between which the blank is passed, there- 15 by enabling practically the entire length of the blank to be rolled and to be properly held and guided during such operation. In the preferred form of my invention, the said connecting members or connectors are flexible 20 and adapted to wind on drums which are located at each side of said rolls. One end of each connector is secured to the respective drum, while the other end is provided with a gripper adapted to be fastened to one end 25 of the blank. This feature of my invention enables me to carry out the rolling operation under much more favorable conditions than when the ends of the blanks are secured to the drums directly; the advantages of this 30 feature are set forth fully in the description following hereinafter. Another feature of my invention relates to the provision of a winding device for the finished blank, which device is separate from the drums mentioned 35 above. Other features of the improved rolling mill relate to the mechanism for driving the drums, to presses interposed between the drums and the rolls, and to various other de- 40 vices and arrangements the construction and advantages of which are developed in the detailed description given below. The new 45 rolling process or method also has a number of valuable novel features, all fully explained hereinafter; among these, I will here mention briefly the step of adjusting the size of the "rolling gap" while the blank is within said 50 gap, and preferably while the blank is in motion; placing the blank under a much higher longitudinal tension than hitherto, and particularly under a tension approaching

the elastic limit; in the case where the rolling operation is performed in a succession of "passes," reducing from pass to pass the forces producing the longitudinal tension under which the blank is placed; placing the 55 blank portion which is on its way to the rolls under a smaller longitudinal tension than the blank portion which has passed between the rolls; and various other features that are pointed out below, in description and claims. 60

Reference is to be had to the accompanying drawings illustrating two typical and satisfactory embodiments of rolling mills embodying my present invention. In said drawings Fig. 1 is a longitudinal vertical section through one form of my improved rolling mill; Fig. 2 is a plan view of such rolling mill and its drive; Figs. 3 and 5 are detail elevations of brake mechanism employed in connection with the drums of the rolling mill; 65 Figs. 4 and 6 are detail elevations of clutch mechanisms used in conjunction with said drums; Fig. 7 is a plan view showing another form of my rolling mill, in which a different drive is employed; Fig. 8 is an end elevation 70 of a press which may be associated with the rolling mills of either Fig. 2 or 7; and Fig. 9 is a detail plan view of a clutch-adjusting device which I prefer to employ in connection with the drives shown in Figs. 2 and 7. 75

In the construction illustrated by Figs. 1 to 6, A indicates a frame in which are suitably journaled the rolls 1, 2, 3, 4, the inner or working rolls 1, 2, which are adapted to engage opposite faces of the blank, being preferably 80 of a smaller diameter than the outer or back- 85 ing rolls 3, 4. Any suitable mechanism (such as, for example, the worm-drive indicated at B, operating to shift a slide C vertically) may be employed to vary the pressure of the rolls, 90 or, in other words, the vertical distance or gap between the blank-engaging rolls 1, 2. At each side of the frame A are located drums 5, 6, of like construction, and to each drum is secured one end of a cable, steel band, or other 95 flexible members 7 and 8 respectively, which might be of the same width as the blank to be treated, the other or free ends of these members being provided with jaws or grippers 9 and 10 respectively, of any suitable construc- 100

tion, for firm connection with the ends of the blank 11 to be rolled, it being understood that this blank is to be passed between the rolls 1, 2. The drums 5, 6 have grooves 12, 13 respectively for the flexible members 7, 8, while recesses 14, 15 respectively are adapted to receive the grippers 9 and 10 whenever the respective member 7 or 8 has been wound entirely on its drum 5 or 6 respectively, as illustrated in Fig. 1 for the flexible member 8.

Provision is made for driving the drum 5 clockwise, or the drum 6 contraclockwise, so that the blank 11 will move toward the right or toward the left. A suitable arrangement for this purpose is shown in Fig. 2 (with details in Figs. 3, 4, 5, 6, and 9); said Fig. 2 also illustrates a drive for the rolls of frame A, said drive being constructed to enable the rotation of said rolls to be reversed. A suitable motor 21, for instance an electric motor, is connected by a clutch 22 with the shaft 23 carrying a fly-wheel 24 and a pinion 25. The latter meshes with a larger gear wheel 26 on a shaft 27, which therefore rotates more slowly than the shaft 23.

The continuously rotating shaft 27 has two driving connections, one of which is adapted to actuate the rolls of the rolling mill, while the other is adapted to operate the drums 5 and 6. Fig. 2 shows the following mechanism or connection for driving the rolls: On the shaft 27 are secured rigidly pinions 35, 37, of which the former meshes with a pinion 36, likewise in mesh with a gear wheel 28 mounted loosely on a shaft 30. On the latter is also mounted loosely a gear wheel 29, in mesh with the pinion 37. The gear wheels 28, 29 will therefore rotate in opposite directions while the shaft 27 is rotating. Said gear wheels carry clutch members 31, 32 respectively, which may be constructed as springs adapted to be engaged by the central clutch member D, held to rotate with the shaft 30, but movable lengthwise thereof. It will be understood that in the central or natural position illustrated, the member D is out of engagement with both springs 31, 32, and the shaft 30 does not rotate; by shifting said member to engage either the spring 31 or the spring 32, the shaft 30 will be coupled either with the gear 28 or with the gear 29, and accordingly caused to rotate in one direction or the other. The longitudinal shifting of member D may be accomplished by means of a lever 33 controlled either manually or otherwise, for instance by means of a hydraulic or pneumatic cylinder 34 to which the medium under pressure may be admitted on one side of the piston or the other, as desired. The shaft 30 carries rigidly a pinion 38, in mesh with a gear wheel 39, which imparts rotation to a suitable train of gears operating the rolls; one gear of this train is indicated at 40, but details have not been illustrated, since mecha-

nisms suitable for this purpose are well-known in the art.

For driving the drums, the following mechanism is provided in Fig. 2: On the shaft 27 is secured rigidly a bevel pinion 41, in mesh with a like pinion 42 on a shaft 43 which carries a worm 44. The latter meshes with a worm gear on a shaft carrying one member 45 of a friction clutch. The other member 46 of this clutch is held to rotate with a shaft 47 aligning with the shaft of the clutch member 45; by means of a shifting lever 48, fulcrumed at 48', the clutch member 46 may be moved lengthwise of the shaft 47, into or out of engagement with the clutch member 45. On the shaft 47 of the drum 5 is secured rigidly a brake disk 49 adapted to be engaged by brake shoes 50, 51. By depressing one of the pedals 52 or 54, motion is imparted to a rod 53, to rock a shaft 55 in one direction or the opposite direction. By means of a crank 56 this shaft is connected with the actuating mechanism of the brake shoes 50, 51, and by means of another crank 57 and toggle links 58, 59 the shaft is connected with the clutch shifting lever 48. These parts are arranged in such a manner that rocking the shaft 55 in one direction will apply the brake shoes and release the clutch, while rocking the shaft in the opposite direction will release the brake and throw in the clutch. A driving mechanism of the same character is associated with the drum 6, Fig. 2 showing a worm 60 on the shaft 43, said worm driving the clutch member 61, the mating clutch member, 62, being mounted on the drum shaft 63 and being adapted to be thrown in or out by the lever 64. The brake disk 65 co-operates with brake shoes 66, 67. Pedals 68, 70 serve to rock the shaft 69 in opposite directions. This shaft has a crank 71 controlling the brake shoes 66, 67, and another crank 72 which controls the shifting lever 64, through the medium of the toggle links 73, 74. The two mechanisms are alike, except that they are constructed to rotate the friction clutch members 45, 61 in opposite directions; for this purpose, the two worms 44, 60 are of opposite pitch, that is to say, one of them is left-hand, and the other right-hand.

The connection of the blank 11 with the drums 5, 6 by means of flexible intermediate members, such as the cables 7, 8, presents numerous important advantages. When the ends of the blank are fastened directly to the drums, according to the former practice, the length of the blank must evidently be at least equal to the distance between the two drums. With the interposition of the flexible members or connectors between the drums and the ends of the blank, the apparatus will accommodate blanks which are much shorter than the distance between the drums. Other ad-

vantages will appear presently as the operation is further described.

At the beginning, one end of the blank is fastened to one of the grippers, for instance the gripper 10, then the other end of the blank is inserted or threaded between the rolls 1, 2 and fastened to the other gripper 9, which for this purpose has been brought as near as possible to the rolls. By means of the mechanism B or its equivalent, the gap between the rolls 1, 2 is adjusted to the width desired for the first operation or "pass" during which, in the case assumed, the blank moves from left to right. For this purpose, the shift lever 33 is moved to couple the shaft 30 with that one of the gears 28, 29 which will cause the roll 1 to rotate counterclockwise and the roll 2 clockwise. Furthermore, the pedals controlling the rock shafts 55 and 69 are operated in such a manner that the shaft 47 will be released from the action of the brake shoes 50, 51 and at the same time coupled with the continuously rotating clutch member 45, while the shaft 69 will be disconnected from the clutch member 61 and placed under the restraining action or resistance produced by the engagement of the brake shoes 66, 67 with the disk 65. The drum 5 will therefore be driven to rotate clockwise, while the drum 6 will be rotated in the same direction by the pull of the blank 11 fed by the rolls 1, 2 and the drum 5. The action of the brake shoes 66, 67 will produce the proper longitudinal tension in that portion of the blank which is on its way to the rolls, while the blank portion which has passed between the rolls and then travels on the drum 5, will be placed under tension by the pull of the drum 5. For this purpose, the clutch member 45 is rotated at a higher speed than that which would be required to give the blank 11 the same linear speed that it obtains from the action of the rolls, and the clutch member 45 is allowed a certain amount of circumferential slip relatively to the clutch member 46, the friction between said clutch members producing the desired tension in the leading portion of the blank, that is, the portion which has passed between the rolls.

It will be obvious that the rolling operation can be continued until the rear end or following end of the blank 11 is almost in contact with the rolls. In other words, practically the entire length of the blank can be rolled, only the short portions held by the grippers 9, 10 constituting waste. This slight waste is of negligible importance, particularly since, as a rule, the blanks passed through my improved rolling have received a preliminary hot rolling treatment which reduces their ends to a condition requiring them to be discarded as waste.

It will be understood that during the first pass the blank will remain straight or plane, since I have assumed a case in which the

blank is originally shorter than the distance between the drums 5, 6. When the gripper 10 has almost reached the rolls 1, 2, the shift lever 33 and the rock shafts 55, 69 are moved in the opposite direction, so that the rolls 1, 2 will rotate to feed the blank 11 from right to left, while at the same time the drum 6 will rotate counterclockwise and become the driving drum, the drum 5 becoming the braking or resistance drum during this second pass of the operation. The gap between the rolls 1, 2 is reduced by the mechanism B, either before the blank begins to move from right to left, or preferably immediately after it has started such movement, it being easier to reduce or narrow the gap while the rolls and the blank are in motion than when they are stationary. When the gripper 9 has come close to the rolls, the machine is stopped, and thereupon the blank is subjected to a third pass (from left to right), and this alternation of passes in opposite directions, with a readjustment of the gap after each pass, is repeated until the blank has been reduced to the desired thickness.

Each individual operation or pass not only reduces the thickness of the blank, but increases its length. Thus after the first pass or one of the later passes, the length of the short blank referred to above will have become greater than the distance between the drums 5, 6, and from that time on, during the subsequent passes, a portion of the blank will wind on the drums, as shown in Fig. 1 with respect to the drum 6. By this time the thickness of the blank has been reduced sufficiently to enable it to bend around the drum readily. During the preceding pass or passes, however, the blank does not wind on the drums, and therefore need not be flexible. I am thus enabled to start with blanks of relatively considerable thickness, which is not possible when the ends of the blank are secured directly to the drums and therefore wind off one of the drums, and on the other, even during the first step or pass.

According to another feature of my invention, the blank, while it is bent around the drums, is not actually formed into a coil on the take-up drum, but when it is desired to coil the finished blank for further treatment or storage and shipment, a separate coiling device is employed for this purpose. Such a device is indicated in Figs. 1 and 2, where 18 is a coil-forming roller located to the left of the drum 6 and driven in any suitable manner, for instance by a belt or chain 18'. The ends of the roller are journaled in bearings one of which, 19, may be swung aside about a vertical pivot 20, so as to clear a path for removing the finished coil lengthwise of the roller. It will be understood that immediately before the last pass, or after such pass, one end of the blank would be disconnected from the gripper 9 or 10, as the case might

be, and secured to the coil-forming roller 18, which would then be rotated to coil the blank, the other end of which would be detached from the second gripper at the proper time.

5 The coil-forming roller is of a diameter of, say, about 50 centimeters. This is the size that has been customary in former practice for the drums when the latter were employed as coil-forming rollers. When the blank is 10 coiled on a separate roller, according to my invention, and not on the drums, these drums may be given a much larger diameter, say 1 meter or over. Increasing the diameter of the drums 5, 6 (in other words, making them 15 considerably larger than the coil-forming roller 18) has very distinct advantages. First, the amount of bending (radius of curvature) given to the blank when it engages the drums 5, 6, is much more favorable to an 20 efficient operation. Not only is the power required for driving the pulling drum reduced as the diameter of the drum increases, (since less power is consumed for the mere bending of the blank), but there is a material 25 reduction of the internal strain which during the bending of the blank arises from the fact that the outer surface of the bent blank is stretched lengthwise of the blank to a greater extent than the inner surface. Obviously, 30 the difference becomes smaller as the drum diameter increases. It should be noted that the power consumed for the mere bending of the blank, decreases at a greater rate than the diameter of the drum; for instance, the 35 power required to bend the blank on a drum of 1 meter diameter is considerably less than one-half the power required to bend the blank on a drum of a diameter of 50 centimeters. Second, on account of the greater radius of 40 curvature, I am enabled to bend considerably thicker blanks on the drum than those which could be worked hitherto.

It will be noted that after the two ends of the blank 11 have been secured to the grippers 9, 10, there is no need of disconnecting the blank from the grippers during the subsequent operations or rolling passes, and this greatly simplifies the manipulation of the apparatus, and reduces the time required for 45 the entire rolling operation, since I avoid the loss of time involved in the repeated attaching and detaching of the blank which were necessary in the practice prevailing hitherto. As I have stated above, the short end portions of the blank, which are held by the grippers 9, 10, do not pass between the rolls 1, 2 and are therefore to be considered as waste. Even these end portions could be rolled, if desired, but for this purpose one 50 end of the blank would have to be disconnected from its gripper and pulled through the rolls, but on account of the loss of time and great inconvenience I find it preferable not to do this, but to allow the gripped ends 55 to be wasted.

I have found that a great improvement can be effected by subjecting the blank to a much greater longitudinal tension than has been customary hitherto. The former practice was to place the blank under a tension just sufficient to prevent looseness in the coiling of the blank. I have ascertained that far superior results are obtained when the longitudinal tension of the blank is increased considerably, even to a point in the neighborhood of the elastic limit (just below such limit). Tests have demonstrated the fact that with increased longitudinal tension of the blank there is a very material reduction of the power required for operating the rolls between which the blank passes during the rolling operation. This increased longitudinal tension is applied, as a rule, to both the leading and the following portion of the blank, in other words, both in advance and in the rear of the rolls. According to the indications obtained by these tests, it would seem that the increased longitudinal tension performs part of the rolling work (reduction in the thickness of the blank and increase 80 in length) which in prior practice is performed exclusively by the rolls. This tension is produced, of course, by the pull of one drum on the leading portion of the blank and by the resistance which the braking device opposes to the motion of the following portion of the blank.

As the thickness of the blank decreases after the successive passes of the rolling operation, the pull and the resistance which place the blank under longitudinal tension are preferably reduced progressively, that is to say, after each pass, in order to obtain a practically uniform longitudinal tension, and particularly in order to avoid stressing the material beyond the elastic limit. The resistance opposed by the braking device may be varied by means of any suitable arrangement, for instance by a handwheel E the turning of which moves the brake shoes 50, 51 or 66, 67 toward or from each other. The pull exerted by the drum 5 or 6 may be varied by adjusting the fulcrums 48' and 64' of the levers 48 and 64 respectively lengthwise of the axes of the shafts 47 and 63 respectively. For this purpose, I may employ the mechanism shown in Fig. 9, where the fulcrum 48' is provided on a slide 94 movable parallel to the axis of shaft 47, by means of a shaft 95 mounted to turn in bearings 96 but held 100 against longitudinal motion. The shaft 95 has a screw portion fitted into a correspondingly threaded hole in the slide 94, and a handwheel 97 is provided to rotate this shaft. It will be understood that an adjusting mechanism of the same character would be provided for the fulcrum 64'. These fulcrum-adjusting mechanisms have been omitted from Figs. 2 and 7, in order not to confuse these views.

At 16 and 17 I have indicated (in Figs. 1, 2, and 7) additional rolls located at opposite sides of the drums 5 and 6 respectively. These additional rolls are used in connection with blanks of a thickness too great to allow them to wind on the drums 5, 6, and of a length too great to allow them to be fastened at once to the grippers 9, 10. Such a blank would first be rolled in the flat condition, 10 without using the drums 5, 6 and the flexible connectors 7, 8, and when the thickness of the blank has been reduced sufficiently (say, to $\frac{1}{6}$ or $\frac{1}{8}$ of an inch) to enable the blank to be bent around the drums 5, 6, its ends would 15 be fastened to the grippers 9, 10, and the operation would then proceed as described above. Generally, the operation would start with one or more passes in which the blank would not be connected with the drums 5, 6; but in the 20 rather exceptional case of short blanks, I might connect them at once with the drums, through the medium of the flexible connectors 7, 8, as first described above.

I have also found that in some cases it is 25 desirable to make the longitudinal tension which results from the pull of one of the drums on the leading portion of the blank, greater than the longitudinal tension which results from resistance opposed by the braking device of the other drum, to the movement of the following portion of the blank. In fact, the longitudinal tension of such following portion may, in this case, be just sufficient to keep the following portion taut. 30 The above-described adjusting devices for the brakes and for the fulcrums of the clutch levers 48, 64 enable the attendant to establish these particular conditions whenever he desires. In all cases where the longitudinal 35 tension of the blank is greater on the leading portion than on the following portion, the difference between the two forces will cause the blank to exert a driving action on the rolls 1, 2, and considerably less power will 40 be required to drive these rolls through the shaft 30. In fact, the pull of the one drum on the leading portion of the blank may be made to exceed the resistance opposed by the other drum to the movement of the following 45 portion of the blank to such an extent that the rolls may be driven exclusively by the action of the traveling blank.

An arrangement of this character is shown in Fig. 7, where the only difference over the arrangement shown in Fig. 2 resides in the fact that no gear drive is provided for the rolls (one of which is shown at 3), and that the driving gear for the clutch members 45, 61 is constructed as follows: Said clutch members 50 are secured rigidly to shafts 81, 82 respectively, rotated continuously in opposite directions through the medium of spur gears 79, 80 respectively likewise secured rigidly to the respective shafts, and of intermediary pinions 78 and 83 in mesh with each other, the pinion 55

78 being also in mesh with the gear 79, while the pinion 83 is in mesh with the gear 80. One of said pinions is driven by the motor 21' through the medium of the clutch 22'; for instance, the said clutch transmits power from the motor 21' to a pinion 75, in mesh with a gear wheel 76 connected rigidly with the shaft 77 having a like connection with the pinion 78. The other parts are the same as in Fig. 2, and bear the same reference 70 75 characters.

One of the advantages of my invention is that the distance between the drums 5, 6 may be made relatively small, and this reduces considerably the danger of lateral distortion of the blank. Such danger may be further counteracted by arranging a suitable press at each side of the rolls, in the immediate vicinity thereof, that is to say, one press between the rolls and the drum 5, and the other 80 85 press between the rolls and the drum 6, to engage, at a point close to the rolls, that portion of the blank 11 which at the time is the following portion. Each of these presses is preferably of such a construction that different 90 adjustments may be made at the portions near opposite longitudinal edges of the blank.

An example of a suitable construction of such presses is shown in Fig. 8, the blank traveling at right angles to the plane of this 95 figure. The upper and the lower press member 85 and 84 respectively engage the blank adjacent to one of its longitudinal edges, while the press members 86 and 87 engage said blank adjacent to its other longitudinal 100 edge. It will be noted that at the central portions of these press members there is left a sufficient clearance for the free passage of the grippers 9, 10, so that these may be brought close to the rolls 1, 2. The press adjacent to the temporarily leading portion of the blank is generally inactive, in other words, its portions 85, 87 are lifted sufficiently to oppose no resistance to the passage of the blank. The other press, adjacent to the 105 temporarily following portion of the blank, is adjusted to exert the proper pressure on the blank whenever required, to exert a braking action additional to that of the brake shoes 50, 51 or 66, 67 and thus provide an 110 additional safeguard against any lateral wandering or deflection of the blank. It is true the great longitudinal tension to which I subject the blank is by itself a powerful safeguard against such lateral deflection of the blank; yet in some cases, and particularly when the following portion of the blank is under considerably less tension than its leading side the assistance of the press on the following side of the blank may be desirable or necessary. 115

As a rule, the right-hand and the left-hand portions of the press will be adjusted to exert equal pressures; in some cases, however (as when the attendant notices a tend- 120 125 130

ency of the blank to shift transversely toward one side), it will be desirable to exert a greater pressure on one side portion of the blank than on the other. I therefore prefer to provide means for the simultaneous vertical adjustment of the upper press members 85, 87 as well as for their independent individual adjustment. A suitable construction of this type consists of upright screws 88, 89 secured to the press members or portions 85, 87 by pins 88', 89' or otherwise, so that the screws can not rotate. The upper portions of the screws are in threaded engagement with the hubs of bevel pinions 88'', 89'' which are held against vertical motion and in mesh with bevel pinions 90' and 92' respectively held to turn with their shafts 90 and 92 respectively. The shaft 92 is tubular and carries a handwheel 93 rigidly. On the shaft 90 is mounted a handwheel 91 held to turn therewith yet slidably lengthwise thereof to bring the handwheel 91 into locking or clutched engagement with the handwheel 93, as illustrated. In this condition, rotation of the handwheel 91 will rotate both shafts 90, 92 alike and therefore effect equal vertical adjustments of the press members 85, 87. By sliding the handwheel 91 outwardly until it is clear of the handwheel 93, the connection between the shafts 90, 92 is interrupted, and each of them may be rotated independently by rotating the respective handwheel 91 or 93, thus effecting an individual adjustment of the press member 85 or 87.

Whenever a supplemental resistance is applied by the press to the movement of the following portion of the blank, care must be taken to adjust properly the resistance which the brake device offers to the movement of said portion. It will be evident that the propelling action which the blank exerts on the rolls depends on the difference between the pulling action of one of the drums on the leading portion of the blank and the total resistance opposed to the movement of the following portion of the blank. Now, this total resistance is the sum of the resistances opposed by the press and by the braking device respectively; therefore, if originally only the braking device was employed, and then the press is brought into action, or if while both are in action the press is adjusted to a different condition, the braking device will have to be adjusted to compensate for the additional or the reduced resistance exerted by the press, in order that the total resistance may remain the same.

The novel mode of operation described above produces a rolled product of very high quality, particularly as regards homogeneity of structure.

The connecting members 7, 8 might (as mentioned hereinbefore) be made of a width substantially equal to that of the blank, say 65 by using steel bands for said members. The

use of relatively wide connecting members would present an additional safeguard against lateral deviation of the blank.

The rolls defining the gap through which the blank passes, are preferably of relatively small diameter, particularly if the blank is to be rolled very thin. For the sake of simplicity, I have shown the gap as formed by the two thin intermediate rolls 1, 2 bearing against two thicker outer rolls 3, 4 respectively, but other arrangements may be employed, for instance one of six rolls, viz, two thin intermediate rolls and four thick rolls engaging them.

In some cases it will be found that during the initial pass or passes, an apparatus such as shown in Fig. 2 can be operated without using the roll drive connected with the shaft 30, but taking care to make the pull on the leading portion of the blank greater than the resistance at the following portion; in other words, the clutch member D could be left in the neutral position illustrated, and the apparatus would operate in substantially the same manner as the one shown in Fig. 7. During subsequent passes, however, it might be found that the action of the drums 5, 6 alone is insufficient to continue the operation, and the roll drive connected with the shaft 30 would have to be thrown in to supplement the action of the drums. The relative share which this gear drive and the action of the drums have in effecting the rotation of the rolls could be varied from the one limit, referred to above, at which the gear drive is entirely inactive, to the other limit at which the pull of one drum on the leading portion of the blank is exactly equal to the resistance on the following portion of the blank, so that the rolls would be rotated by the gear drive alone.

I have described above the provision of presses, such as the one shown in Fig. 8, for the purpose of preventing, or helping to prevent, any lateral deviation of the moving blank. Other means may be used for the same purpose, for instance the well-known expedient of not making the rolls truly cylindrical, but giving them such a profile that the edge portions of the blank will be rolled slightly thinner than its central portion. When employing presses, these may also be provided with lateral guides for the blank. I may add that whenever one of the press members 85 or 87 is adjusted downward individually (with the handwheels 91, 93 disconnected from each other) to increase the pressure on that edge portion of the blank, the other member 87 or 85 respectively should be raised individually to reduce the pressure on the other edge portion of the blank by the same amount, so that there will be no change in the aggregate pressure of the two members, since any such change would require a re-adjustment of the brake shoes 50,

100

105

110

115

120

125

130

51 or 66, 67 as well if the total resistance on the following portion of the blank is to be kept constant. As a rule, the brake shoes 50, 51 and 66, 67 are adjusted to exert a less

5 powerful action when the pulling action of one drum on the leading portion of the blank exceeds the resistance at the following portion of the blank, than when the rolls are driven exclusively or at least predominantly 10 by the drive gear, such as the one connected with the shaft 30.

As the slip clutches 45, 46 and 61, 62 have to transmit considerable power, their friction surfaces should be exceptionally large and 15 in some cases it is desirable to provide for cooling them, as by air or water.

Instead of the particular power drives illustrated, I might employ others, for instance, an electric drive for the drums 5 and 20 6, and in this case the braking action might also be effected electrically, for instance by making the driving motor function as a braking generator as well, or by an interposed eddy current brake. A specially desirable 25 arrangement would consist of two parts, one of them rotating continuously and the other, which is held to rotate with the drum, being coupled electromagnetically with said continuously rotating part, but with an adjustable 30 slip action, during the time that such drum exerts a pulling or take-up action; during the period that the drum supplies the blank to the rolls, the drum would also slip relatively to said continuously rotating part, 35 but in a different manner. This will be understood upon considering the conditions obtaining if said continuously rotating part is given a high number of revolutions as compared with the relatively low number of revolutions of the slowly rotating drum. In this case the reversal of the drum from rotation 40 in one direction (pulling, or winding-on of the connector 7 or 8) to rotation in the opposite direction (paying out, or winding-off of 45 said connector) will involve only a relatively small variation of the slip action, such as will offer no difficulty when an electric drive of the character just referred to is employed. Such an arrangement would also have the 50 further advantage that the pulling energy could be maintained uninterruptedly during the reversal of the drum from rotation in one direction to rotation in the opposite direction, through an intermediate condition 55 where the drum, for just a moment, would have no rotation at all. This would be of particular importance when my improved method is carried out with very high pulling forces or very high longitudinal tension in 60 the blank.

The same effect might be obtained with an electric drive in which an electromagnetic field would rotate continuously, instead of a continuously rotating part of the machine or apparatus, so that such field would exert a

65 tractive effort on the drum even when the latter is stationary relatively to the adjacent parts.

In some cases it is desirable to make special provision for insuring a perfectly even entrance of the blank between the rolls. For this purpose I may employ in lieu of the presses described above, or in addition thereto, tension rolls of a type well-known in connection with machines for straightening sheet 70 metal. As a rule, however, such tension rolls would be employed in connection with my improved rolling mill only after the blank has been rolled down to a relatively small thickness, so that it can not be injured by 75 being bent between said tension rolls.

80 Various modifications may be made without departing from the nature of my invention as set forth in the appended claims.

I claim:

85 1. A rolling mill having rolls, drums located at each side of said rolls and adapted for connection with the blank, a slip clutch for the actuation of each of said drums, a braking device for each drum, and a unitary controlling mechanism for each slip clutch and the braking device of the same drum, to release the braking device when the clutch is thrown in, and to apply the braking device when the clutch is thrown out. 95

90 2. A rolling mill according to claim 1, in which there is an electric drive for each drum, and in which the braking device is operated by an electric current and is either a separate current brake or the motor connected to function as a generator. 100

105 3. A rolling mill according to claim 1, in which there is an electric drive for each drum, and in which the braking device is operated by an electric current and is a separate current brake one member of which rotates continuously at a relatively high speed. 110

4. A rolling mill according to claim 1, in which there is an electric drive for each drum, and in which the braking device is operated by an electric current and is a separate current brake one member of which rotates continuously at a relatively high speed, said brake also serving as a slip clutch 115 for driving the drum.

120 5. A rolling mill according to claim 1, in which there is an electric drive for each drum, and in which the braking device is operated by an electric current and comprises an electromagnetic field rotating continuously at a relatively high speed, that part of the electric mechanism which is connected with the drum, slipping with respect to said field both during the driving condition and during the braking condition. 125

6. A rolling mill, comprising rolls, a drum at the side of said rolls for drawing material therethrough, a constantly driven motor, a driving connection between said motor and 130

said rolls including a clutch, and a driving connection operatively connected to said first connection between the motor and the clutch for driving said drum.

5. 7. In a rolling mill as claimed in claim 6, a slip coupling in said second driving connection.

8. In a rolling mill, a pair of rolls, drums at the sides of said rolls upon which a blank 10 may be wound to be drawn back and forth through said rolls, and driving means for said drums including a continuously rotating shaft, driving connections from said shaft to said drums to cause said drums to 15 rotate in opposite directions, slip clutches in said driving connections, and means to engage one of said clutches while permitting the other clutch a slip, whereby to draw said blank through said rolls.

20. 9. In a rolling mill, a pair of rolls, drums at each side of said rolls upon which a blank may be wound to be drawn back and forth through said rolls, and driving means for said drums including a continuously driven 25 shaft, driving connections from said shaft to said drums to cause said drums to rotate in opposite directions, slip clutches in said driving connections, means to engage one of said clutches while permitting the other 30 clutch a slip, whereby to draw said blank through said rolls, means for braking said drums, and means for controlling said clutches and braking means so that one of said clutches may be engaged when the other 35 drum is braked.

10. In a rolling mill as claimed in claim 8, means for exerting different vertical pressures on opposite longitudinal edges of the material.

40. 11. A rolling mill comprising rolls, drums for drawing material therethrough, a motor adapted to rotate in one direction, a driving connection between said motor and said rolls for driving said motor and including clutching 45 means for driving said rolls in either direction, and a driving connection operatively connected to said first driving connection between said motor and said clutching means for driving said drums in opposite 50 directions.

12. A rolling mill as in claim 11, and clutches in said second driving connection between said first driving connection and each of said 55 drums.

13. A rolling mill as in claim 11, clutches in said second driving connection between said first driving connection and each of said drums, and means for braking each of said 60 drums.

14. A rolling mill as in claim 11, clutches in said second driving connection between said first driving connection and each of said drums, and means for braking each of said 65 drums together with control means for caus-

ing braking of each drum when the clutch thereof is disengaged.

15. A rolling mill for thick blanks having rolls, drums at each side of said rolls of large diameter, means for actuating said drums, 70 flexible connectors each having one end secured to one of said drums and the other provided with a gripper adapted to secure one end of the blank, said connectors being adapted to wind on the respective drums, and a coil-forming device additional to said drums, said device comprising a winding roll of a diameter considerably less than the diameter of said drums.

16. A rolling mill for thick blanks having rolls, drums at each side of said rolls of large diameter, means for actuating said drums, 80 flexible connectors each having one end secured to one of said drums and the other provided with a gripper adapted to secure one 85 end of the blank, said connectors being adapted to wind on the respective drums, and a coil-forming device additional to said drums, said device comprising a winding roll of a diameter considerably less than the diameter of 90 said drums, and means connected to said drum actuating means for driving said winding roll.

17. In a rolling mill, a pair of rolls, drums for drawing material through said rolls, a 95 pair of shafts, means for rotating said shafts continuously in opposite directions, a slip coupling between each of said shafts and one of said drums, means to engage one of said 100 couplings and means to disengage the other of said couplings to draw a blank through said rolls.

18. In a rolling mill, a pair of rolls, drums for drawing material through said rolls, a pair of shafts, means for rotating said shafts 105 continuously in opposite directions, a slip coupling between each of said shafts and one of said drums, means to engage one of said couplings and means to disengage the other of said 110 couplings to draw a blank through said rolls, means for braking said drums, and means controlled by said coupling disengaging means to actuate said braking means.

19. The method of rolling which consists in passing a blank under tension between rolls while exerting different vertical pressures on opposite longitudinal edges of the blank before it reaches the rolls, to counteract any tendency of the tension to cause lateral deviation of the blank in the rolls.

20. In a rolling mill, a pair of rolls, means for drawing a blank under tension through said rolls, and means for exerting different vertical pressures on opposite longitudinal edges of the blank before it reaches the rolls, to counteract any tendency of the tension to cause lateral deviation of the blank in the rolls.

21. In a rolling mill, a pair of rolls, drums at the sides of said rolls upon which a blank 130

may be wound to be drawn back and forth through said rolls, means constantly urging said drums to turn in opposite directions, and means to decrease partially the effect of said last named means on one of the drums so as to permit the other drum to draw the blank through the rolls.

5 In testimony whereof I have hereunto set my hand.
